RELEASE FOR COIN CONTROLLED
SWITCHESElmer L. Lipp, Los Angeles, Calif., assignor, by
mesne assignments, to Refining, Inc., Reno,
Nev., a corporation of Nevada

Application November 7, 1932, Serial No. 641,496

7 Claims. (Cl. 194—61)

My invention relates to time limit controlling devices of the general character disclosed in my copending application Serial No. 637,861, filed October 15, 1932, and entitled Coin controlled switch, and also constitutes an improvement upon the device disclosed in this copending application.

In devices of the character to which my invention relates, a control element is employed in conjunction with means for placing the control element in active condition and a timer operative to return the control element to inactive condition at the end of a prescribed period of time.

It is an object of my invention to provide a device of the above general character having means which will operate in consequence of the stopping of, or an attempt to stop, the timing device to return the control element to inactive condition so that before use of the device or means with which the control element is associated can be had, the control element must be placed again in active condition, which in most devices of this general character requires the use of a coin. As an example of the utility of my present invention, it may be stated that the time limit controlling device shown in my present application and in my copending application, Serial No. 637,861, is used in connection with the lease of devices or the sale thereof on deferred payment plans, it being agreed between the seller, and the purchaser that for each working day a coin will be deposited in the controlling device associated with the mechanism being leased or sold, it being the intention that the coin shall be deposited in the controlling device at the beginning of each working day so that at the end of a month's period the seller may depend upon collecting from the coin box of the device substantially twenty-five coins. The timing means of a device of this character generally consists of a synchronous motor which is energized whenever the switch forming the control element of the device is closed in consequence of the placing of a coin in the timing device. Such synchronous

motors may be stopped by turning off the supply of electric energy thereto, as by pulling the main switch leading to the mechanism or device to which the timing device is attached. Accordingly, the period of time demarcated by the timing means associated with the control element may be utilized in the ordinary timing device such as shown in my copending application Serial No. 637,861 through portions of a number of consecutive days, by starting the timing device by use of a coin on the first day, using the mecha-

nism with which the timing device is associated for a short period of time, and then pulling the main switch so as to stop the synchronous motor constituting the timing means. On a succeeding day the main switch may be closed and the mechanism made use of for another short period of time during which the synchronous motor will operate. In this manner the device may be used on consecutive days by use of a coin on the first of these consecutive days, in defeat of the intent that the timing device should require the deposit of a coin of specified value on each working day.

Accordingly, my invention has for its object to provide a coin controlled switch having means for releasing the switch when the timing means associated therewith is stopped, as by the cutting off of the supply of electric current to a synchronous motor constituting such means.

Further objects and advantages of the invention will be made evident throughout the following part of the specification.

Referring to the drawing, which is for illustrative purposes only,

Fig. 1 is an elevational view of a coin controlled switch embodying my invention, this view showing the control element or switch of the device in inactive or open condition.

Fig. 2 is an elevational view similar to Fig. 1, showing the parts of the device disposed in their relative positions when the switch is closed.

Fig. 3 is an enlarged fragmentary section on a plane represented by the line 3—3 of Fig. 2.

The form of my invention disclosed in the drawing includes a control element 10 in the form of a switch consisting of upper and lower spring contact members 11 and 12 secured to metal posts 13 and 14 mounted in an insulator 15 carried by a supporting plate 16. The control element 10 is adapted to control the operation of a device such as a motor 17, and accordingly the controlling element or switch 10 is inserted in a conductor 18 leading from a main switch 20 to one terminal 21 of the motor 17, and a second conductor 22 is shown connecting the switch 20 with the other terminal 23 of the motor 17, the conductor 22 being shown with a switch 24' therein whereby the operation of the motor 17 may be stopped by opening the circuit when the switches 10 and 20 are closed. For closing the switch 10, I provide a lever 24 pivotally secured to the plate 16 by use of a pivot member 25 and having a body of insulation 26' on the rightward end thereof adapted to engage the member 11 when the lever 24 swings from the position in which it is shown in Fig. 1

to the position in which it is shown in Fig. 2, and to force the member 11 into engagement with the member 12 to close the switch 10 as shown in Fig. 2. The leftward end of the lever 24 has 5 a latch member 26 secured thereto by a pivot member 21. A spring 28 is secured to a leftwardly projecting arm 30 formed on the latch member 26 in a position to rotate the latch member 26 and the lever 24 in anti-clockwise direction. For raising the latch member 26 from its 10 position of Fig. 1 to its position of Fig. 2 whereby to swing the lever 24 in clockwise direction and close the switch 10, I provide a coin controlled actuator 31 having a forwardly projecting knob 32 whereby it may be rotated in anti-clockwise 15 direction from the position in which it is held in Fig. 1 by a spring 33 to the position in which it is shown in Fig. 2 so that a projection 34 carried by the member 31 will move rightwardly and upwardly from its position of Fig. 1 so as to engage a finger 35 formed in leftwardly projecting position on the upper portion of the latch member 26, and to carry the finger 35 and the latch member 26 upwardly to a position, as shown in 20 Fig. 2, wherein the finger will be engaged by a spring catch 36 projecting forwardly through an opening 37 in the plate 16. Projecting forwardly from the plate 16 is a small plate 38 providing a vertical slot 40 through which the finger 35 25 projects and in which the finger 35 may be moved vertically by the projection 34 of the member 31. Adjacent the slot 40 a tongue 41 is bent rightwardly from the plate so as to provide a sloping face or cam adapted to be engaged by 30 the shoulder 42 of the member 26 so that as the member 26 moves upwardly it will also be rotated slightly in clockwise direction as it moves into the raised position in which it is shown in Fig. 2. It will be perceived that the spring 33 35 has one end thereof secured to the member 31 and the other end secured to the plate 38. A coin receiver 43 is provided having a coin opening 44 leading to a slot indicated by dotted lines 45 so that when a coin is placed in the opening 44 and moved rearwardly therein, it will drop 40 through the slot 45 into a pocket 46 formed in the periphery of the member 31, as indicated by dotted lines 47. This coin indicated by dotted lines 47 projects from the periphery of the member 31 so as to engage a latch member 50 pivotally mounted on a screw 51 and provided with a spring 52 for normally rotating it in clockwise direction so as to be in position to engage a shoulder 53 on the member 31 and thereby prevent 45 movement of the member 31 in anti-clockwise direction beyond a definite point. The latch member 50 is raised by the coin in the pocket 46 so that it will not drop into engagement with the shoulder 53 as the member 31 is rotated in anti-clockwise direction, thereby permitting the 50 movement of the member 31 to be continued to such an extent that the projection 34 thereof will engage and raise the finger 35 of the member 26 into the raised or actuated position in which such member 26 is shown in Fig. 2. When the pocket 46 passes downwardly beyond the latch member 50, the coin therein will drop into a coin receptacle indicated by dotted lines 55 in Fig. 2. Release of the knob 32 will permit the spring 33 to return the member 31 to its initial 60 position of Fig. 1.

The closing of the switch 10 in consequence of the raising of the member 26, by use of the coin controlled actuating means 31, closes the circuit consisting of conductors 18 and 22 so that the

electrical device or mechanism represented by the motor 17 may be operated. Mounted on the upper part of the plate 16 is a chronometer element consisting of a small synchronous motor 56 which is connected through conductors 57 and 58 with the conductors 18 and 22, so that the closing of the switch 10 in consequence of the operation of the actuating means 31 through use of a coin will energize the motor 56 to rotate a pinion 60 which, through an idler 61, will transmit rotation to a timing disc 62 having a forwardly projecting pin 63. The rotation of the disc 62 in anti-clockwise direction, as indicated by the arrow 64 in Fig. 2, will carry the pin 63 from its position in Fig. 2 through a circle of rotation 15 65 so that at the expiration of a period of time determined by the speed of the motor 56 and the gear ratio existing between the members 60 and 62, the pin 63 will reach a position of engagement 66 with a rightwardly projecting shoulder 67 20 formed at the lower end of the member 26, and the continued movement of the member 63 downwardly from the position 66 will cause the member 26 to rotate on the pivot 21 in rightward 25 direction until the point 68 of the finger 35 is moved rightwardly from engagement with the catch 36, whereupon the member 26 will drop to the lowered position in which it is shown in Fig. 1, swinging the lever 24 and releasing the 30 switch member 11 from engagement with the member 12, thereby opening the circuit consisting of the conductors 18 and 22 and prohibiting operation of the motor 17 until the switch 10 is again closed in consequence of the use of a coin in the actuating means 31, as previously 35 described herein.

From the foregoing it will be perceived that the timing disc 62 is rotated only when the main switch 20 is closed so as to energize the synchronous motor 56. In order to prevent 40 surfeituous stopping of the timing motor 56 whereby to extend the period of time the control element or switch 10 remains closed after the use of a coin, I provide a means 70 for opening the switch 10 should the main switch 20 be opened. 45 Such means 70 comprises an electromagnet 71 having a coil 72 which is connected to the conductors 18 and 22 in such a manner that when the main switch is closed, the coil will be energized, whereby producing a magnetic flux in a 50 field member 73 forming part of the electromagnet to move the armature 74 associated therewith, against the tension of a spring 75, from the open position in which it is shown in Fig. 1 to its closed position of Fig. 2. Extending downwardly from the armature 74 is a plate 76 having a rightwardly bent lower end portion 77 with a slot 78 therein adapted to be engaged by a pin 79 in the upper end of a lever 80, the lower end of which is pivotally attached to the 60 plate 16 by means of a pivot post 81. Near the upper end of the lever 80 is a forwardly projecting pin 82 which, in consequence of the swinging of the lever 80 by movement of the armature 74, moves between the positions in which it is shown in Figs. 1 and 2. On the upper end of the member 26 a dog 84 is pivotally secured by means of a rivet 85 and is normally held in erect position by means of a flat spring 86. When the member 26 is in raised position as shown in 65 Fig. 2, the dog 84 is held in the path of movement of the forwardly projecting pin 82. Should the main switch be open at the time the coin controlled actuating means 31 is operated to actuate the member 26, the dog 84 will be moved 70 75

up into a position to the left of the pin 82 in Fig. 1. The closing of the main switch 20 subsequent thereto will energize the electromagnet 71 and cause the armature 74 thereof to swing 5 leftwardly, thereby moving the pin 82 leftwardly from its position of Fig. 1 to its position of Fig. 2, the pin 82 during this movement engaging the dog 84 and swinging it leftwardly against the action of the spring 86 to permit the pin 82 10 to move into its leftward position shown in Fig. 2, after which the spring 86 will return the dog 84 to erect position. Should the main switch 20 be then opened so as to de-energize the electromagnet 71, the armature 74 will be released, and the pin 82 will be moved rightwardly from its 15 position of Fig. 2, engaging the dog 84 and moving the member 26 rightwardly to cause the finger 35 to move out of engagement with the catch 36 to permit the member 26 to return to lowered 20 position, resulting in opening of the switch 10. Should the main switch 20 be closed before the operation of the coin controlled actuating means 31 to close the switch 10, the dog 84 will be 25 raised into a position to the right of the pin 82 in Fig. 2, and a later release of the main switch 20 will result in a movement of the pin 82 in rightward direction to engage the dog 84 and thereby release the member 26 as above described.

From the foregoing it will be perceived that 30 my present invention defeats any attempt to delay or extend the period of time the control element 10 remains in inactive condition, for the stopping of the timing motor 56 by pulling the main switch 20 will result in releasing the control element 10 so that the deposit of another 35 coin will be required to again return the same to active condition.

Although I have herein shown and described 40 my invention in simple and practical form, it is recognized that certain parts or elements thereof are representative of other parts, elements, or mechanisms which may be used in substantially the same manner to accomplish substantially the same results; therefore, it is to be understood 45 that the invention is not to be limited to the details disclosed herein but is to be accorded the full scope of the following claims.

I claim as my invention:

1. A time limit device of the character described, for permitting or preventing use of a device or mechanism, including: a control element adapted to be placed in active and inactive condition and to be associated with said device or mechanism in a manner to respectively permit or prevent the use thereof; actuating means for placing said control element in active condition; a catch; a latch member connected to said control element and being adapted to engage said catch; a time limit means for disengaging said 50 latch member and said catch so as to return said control element to inactive condition at the end of a prescribed period; and means operating in consequence of the stopping of said time limit means during said period to disengage said latch member and said catch.

2. A time limit device of the character described for permitting or preventing use of a device or mechanism, including: a control element adapted to be placed in active and inactive condition and to be associated with said device or mechanism in a manner to respectively permit or prevent the use thereof; actuating means for placing said control element in active condition; a catch; a latch member connected to said control element and being adapted to engage said 55

catch to hold said control element in active condition; conductors forming an electric circuit; an electrically operated time limit means connected to said circuit, for disengaging said latch member from said catch to return said control element to inactive condition at the end of a prescribed period; and an electrical releasing device connected to said circuit and operating in consequence of the reduction of flow of electric energy in said circuit to release said latch member 10 from said catch. 5

3. A time limit device of the character described for permitting or preventing use of a device or mechanism, including: a control element adapted to be placed in active and inactive condition and to be associated with said device or mechanism in a manner to respectively permit or prevent the use thereof; actuating means for placing said control element in active condition; a catch; a latch member connected to said control element and being adapted to engage said catch to hold said control element in active condition; conductors forming an electric circuit; an electrically operated time limit means connected to said circuit, for disengaging said latch member from said catch to return said control element to inactive condition at the end of a prescribed period; and an electromagnetic releasing device connected to said circuit, said device having an armature magnetically released when the flow of electric energy in said circuit drops below a predetermined minimum, said armature having an engagement member for disengaging said latch member from said catch upon release of said armature. 15 20 25 30 35

4. A time limit device of the character described, for permitting or preventing use of a device or mechanism, including: a control element adapted to be placed in active and inactive condition and to be associated with said device or mechanism in a manner to respectively permit or prevent the use thereof; coin controlled means operative to place said control element in active condition; a catch; a latch member connected to said control element and being adapted to engage said catch to hold said control element in active condition; conductors forming an electric circuit; an electrically operated time limit means connected to said circuit, for disengaging said latch member from said catch to return said control element to inactive condition at the end of a prescribed period; and an electromagnetic releasing device connected to said circuit, said device having an armature magnetically released when the flow of electric energy in said circuit drops below a predetermined minimum, said armature having an engagement member for disengaging said latch member from said catch upon release of said armature. 40 45 50 55

5. A time limit device of the character described, for permitting or preventing use of a device or mechanism, including: a control element adapted to be placed in active and inactive condition and to be associated with said device or mechanism in a manner to respectively permit or prevent the use thereof; actuating means for placing said control element in active condition; a catch; a latch member connected to said control element and being adapted to engage said catch to hold said control element in active condition; conductors forming an electric circuit; switch means automatically opening and closing said circuit in accordance with the placing of said control element in active and inactive conditions; an electrically operated time limit means 60 65 70 75

- connected to said circuit, for disengaging said latch member from said catch to return said control element to inactive condition at the end of a prescribed period; and an electromagnetic re-
- leasing device connected to said circuit, said device having an armature magnetically released when the flow of electric energy in said circuit drops below a predetermined minimum, said armature having an engagement member for disengaging said latch member from said catch upon release of said armature.
6. A time limit device of the character described, for permitting or preventing use of a device or mechanism, including: a control element adapted to be placed in active and inactive condition and to be associated with said device or mechanism in a manner to respectively permit or prevent the use thereof; a movable member adapted to be moved through a prescribed path of movement, said member engaging and placing said control element in active condition when so moved; and duplex means for returning said control element to inactive condition independently of said movable member, said means comprising a time limit means for returning said control element to inactive condition at the end of a prescribed period, and means operating in consequence of the stopping of said time limit means during said period to return said control element to inactive condition.
7. A time limit device of the character described, for permitting or preventing use of a device or mechanism, including: a control element adapted to be placed in active and inactive condition and to be associated with said device or mechanism in a manner to respectively permit or prevent the use thereof; a movable member adapted to be moved through a prescribed path of movement, said member engaging and placing said control element in active condition when so moved, and means for returning said control element to inactive condition through a path of movement separate from the path of movement of said movable member, said means comprising a time limit means for returning said control element to inactive condition at the end of a prescribed period, and means operating in consequence of the stopping of said time limit means during said period to return said control element to inactive condition.

ELMER L. LIPP. 25
